C. J. GREENSTREET,

PROCESS OF TREATING HEAVY HYDROCARBON OILS

APPLICATION FILED MAR. 13, 1911.

CHARLES J. GREENSTREET, OF DENVER, COLORADO.

PROCESS OF TREATING HEAVY HYDROCARBON OILS.

1,110,923.

Specification of Letters Patent. Patented Sept. 15, 1914.

Application filed March 13, 1911. Serial No. 614,125.

To all whom it may concern:

Be it known that I, CHARLES J. GREENSTREET, a citizen of the United States, and a resident of the city and county of Denver, 5 in the State of Colorado, have invented a certain new and useful Process of Treating Heavy Hydrocarbon Oils, of which the following is a specification.

My invention relates to the process of 10 treating heavy hydrocarbon oils set forth in my copending application for patent therefor Serial Number 696,891 filed May 13, 1912; and the present invention provides for the testing and control of the operation 15 of said process.

The accompanying drawing, which forms part of this specification and wherein like symbols refer to like parts wherever they occur, is a diagrammatic view of an apparatus suitable for carrying out my process.

The apparatus illustrated in the accompanying drawing comprises a closed receptacle 1 for the crude oil, a boiler or steam generator 2, a furnace 3, a heating coil or 25 pipe system 4 in position to be heated by said furnace, and a series of condensing tanks 5, 6, 7. The oil receptacle is connected with an air pump or other suitable source of pressure to maintain pressure on the oil; 30 and it has an outlet pipe 8 which communicates with the heating coil through an atomizer 9 and a pipe 10. The boiler or generator likewise has a pipe 11 which communicates through said atomizer with said pipe 10, which in turn communicates with the heating coil. The heating coil has an outlet pipe 12 which leads into the lower portion of the first condensing tank 5, and the first condensing tank has an outlet pipe 35 13 leading from the upper portion thereof to the lower portion of the second condensing tank; and each successive tank is provided with an inlet pipe opening near its upper portion. Extending from the outlet 40 pipe 12 of the heating coil, is a pipe or by-pass 14 which leads into the fire chamber of the furnace or elsewhere, as desired, and is there provided with a suitable test burner 15. Each of the condensing tanks has an 45 outlet or draw-off pipe 16 at or near its bottom, through which the hydrocarbon oil may be drawn off for test or use as required. The several pipes are controlled by suitable valves, 17, 18, 19, 20, 21, 22, 23, 24, 25, 26, 50 provided therefor.

In the practice of my process, the furnace is first fired until the heating coil or pipe system therein is heated to a temperature in excess of one thousand degrees Fahrenheit; and this temperature is maintained throughout the operation. The best results are usually produced with a cherry red heat. During this initial heating, communications with the heating coil are cut off. When the furnace has become sufficiently hot, the 55 valves controlling the communication of the heating coil with the steam generator and with the test jet or burner are opened so that steam alone is passed through the heating coil and out through the test burner. The 60 valve controlling the outlet pipe from the crude oil receptacle is then opened gradually so as to allow oil in increasing quantity to pass through the atomizer into the heating coil and out through the test jet or burner. 65 Initially, of course, pure steam issues from the test jet or burner and later an increasing quantity of hydrocarbon vapor issues therewith. So long as the mixture contains only a slight percentage of hydrocarbon, it 70 is not inflammable; but with a larger percentage of hydrocarbon vapor, the mixture becomes inflammable and is ignited by the furnace heat. If the hydrocarbon vapor is in excess, the flame from the test jet or 75 burner becomes smoky; whereas a bluish flame indicates that the steam and oil vapor are mixed in proper proportion. When the mixture issues from the test jet with such bluish flame, the valve in the pipe leading 80 to the condensing tank is opened, and the valve in the by-pass leading to the test jet or burner may be closed; or it may be open continuously or at intervals to permit a 85 small quantity of the product to burn as an indication of the operation of the process. When the uncondensed product, thus tested, is found to be satisfactory, it then passes 90 from the heating coil into the first condensing tank, where the heavier hydrocarbon oils condense, while the lighter hydrocarbons either condense initially in this tank or pass into the other condensing tanks successively. In the course of the operation, the first condensing tank becomes quite hot 95 with the result that any of the light hydro-

2
carbons that may have condensed therein initially, are redistilled and passed over into one of the succeeding tanks. By this arrangement of a series of successive condensing tanks, the hydrocarbons in each tank are successively lighter than those in the next preceding tank; but this separation can readily be effected by condensing the entire product in a single tank and then fractionally distilling such product.

10 In carrying out the process, a high temperature must be maintained in the heating coil or pipe-system, a cherry red heat usually giving the best results in practice with crude 15 paraffin base oils. It is to be noted that if the crude oil alone were passed through the coils at this temperature, its value would be seriously impaired; whereas a proper proportion of steam commingled therewith aids 20 materially in the conversion of the crude oil into the lighter hydrocarbons. As the composition of the crude oil varies greatly, even when it comes from adjacent wells or even in the life of a particular well, I prefer to 25 test the proper proportion of steam and oil by means of the test burner as above described, rather than by other means, especially as this test burner affords a convenient means of testing the proportion at any time 30 during the operation of the process. Where, however, the composition of the crude oil is substantially uniform, it may be advisable to thoroughly emulsify the oil and water together initially, instead of depending upon 35 the atomizer.

The proportion of water to oil used in my process admits of considerable variation, especially as the composition of the crude oil itself varies and water is one of the ingredients thereof. One way of testing the quantity of water is by comparing resulting products with the products resulting from ordinary fractional distillation of the same oil; the quantity of water should be increased until the proportion of light hydrocarbons in the product greatly exceeds the proportion of the same light hydrocarbons resulting from the ordinary fractional distillation process. With ordinary crude oils 45 like those from the Illinois field, it is preferable to use crude oil and water in substantially equal proportions, but the quantity of water may very greatly exceed that of the crude oil. So long as the water is used in 50 sufficient quantity to bring about the conversion of heavier hydrocarbons into lighter hydrocarbons, it is of advantage. The excess water condenses at the bottom of the condensing tanks whence it may be drawn off. 55 It is to be noted that the temperature of the heating coil influences the products, but that the products which result from the treatment of given crude oil at a given temperature are of a definite and uniform quality. For instance, certain definite and uni-

form products can be obtained from a given crude oil by treating the same at a red heat; whereas certain other products also of a definite and uniform quality will be obtained by treating another portion of the same 70 crude oil at a bright cherry heat. The temperature may be varied therefore to suit the requirements of the desired product.

Obviously, my process can be carried out with other apparatus than that illustrated in 75 the accompanying drawing. So, too, the process admits of considerable variation without departing from my invention.

What I claim is:

1. The process of procuring light hydrocarbons from crude oil which consists in keeping a pipe system at a temperature above one thousand degrees Fahrenheit, said system being clear of obstructions tending to retard the flow of the oil, passing such oil 80 continuously through said pipe system while commingled with steam in such proportion that the resulting product is capable of burning with a bluish flame, and then permitting such product to condense. 90

2. The process of treating crude oil which consists in submitting a current of said oil commingled with steam to a heat in excess of one thousand degrees Fahrenheit, igniting a portion of the hot products, varying the proportion of oil and steam until the test flame becomes bluish, and then condensing the remaining product. 95

3. The process of treating crude oil which consists in submitting a current of said oil 100 commingled with steam to a heat in excess of one thousand degrees Fahrenheit, igniting a portion of the hot products, varying the proportions of oil and steam until the test flame becomes bluish, and then fractionally 105 condensing the remaining product.

4. The process of treating crude oil which consists in submitting a current of said oil commingled with steam to a cherry red heat, 110 igniting a portion of the hot products, varying the proportions of oil and steam until the test flame becomes bluish, and then condensing the remaining product. 115

5. The process of treating crude oil which consists in passing steam through a heating coil at a heat in excess of one thousand degrees Fahrenheit, and thence through a test burner, injecting a small proportion of oil into the steam before it enters said heating coil and progressively increasing said proportion until the uncondensed product burns with a bluish flame, and then fractionally condensing the remainder of the product resulting from the treatment of the mixture of oil and steam in such proportion. 120

6. In the art of treating crude hydrocarbon oil with steam and at a temperature in excess of the distillation points of the heavier hydrocarbon components thereof, the method of determining the amount of such steam, 130

which consists in igniting a portion of the issuing vapor and gradually changing the proportion of the oil until the test flame becomes bluish.

5 7. The process of converting crude oil into light hydrocarbons, liquid at ordinary atmospheric temperatures, which consists in atomizing the crude oil with steam, passing the mixture continuously through a pipe
10 system maintained at a substantially cherry

red heat, igniting a portion of the hot product, varying the proportion of crude oil and steam so that the flame burns without smoking, and condensing the remaining product.

CHAS. J. GREENSTREET.
